UNITED STATES PATENT OFFICE

ANTHONY MACCHIA, OF NEW YORK, N. Y.

FRUIT PRESS

Application filed December 13, 1930. Serial No. 502,064.

This invention relates, generally, to presses; and the invention, has reference, more particularly, to a novel press adapted to squeeze the juices or liquid content out of fruit and the like.

Fruit presses, as heretofore generally constructed, are more or less unsatisfactory in operation because of the difficulty of removing the fruit pulp therefrom after the juices have been squeezed from the fruit.

Commonly the bed or bottom of the press is adapted to be removed from the press by sliding the same endwise therefrom so that the pulp may be pushed downwardly out of the press, but in practice these bottoms or beds tend to stick in the press owing to the pressure of the overlying fruit pulp and can be removed only with great difficulty.

The principal object of the present invention is to provide a novel fruit press so constructed and arranged that the bed thereof may readily be removed from the same after the pressing operation, thereby enabling ready removal of the compressed pulp from the machine.

Another object of the present invention lies in the provision of a novel fruit press which is of simple construction and is easily operated, the said press being extremely powerful in that the same will remove substantially all liquid from the material pressed.

Other objects of this invention, not at this time more particularly enumerated, will be clearly understood from the following detailed description of the same.

The invention is clearly illustrated in the accompanying drawings, in which:

Fig. 1 is a view in front elevation of the novel fruit press of this invention.

Fig. 2 is an enlarged sectional view taken along line 2—2 of Fig. 1.

Fig. 3 is a sectional view taken along line 3—3 of Fig. 2.

Fig. 4 is an enlarged fragmentary view of a portion of the structure shown in Fig. 2 but illustrates the machine bed in its lowered position ready for removal from the machine; and

Fig. 5 is an enlarged fragmentary sectional view taken along line 5—5 of Fig. 2.

Similar characters of reference are employed in all of the above described views, to indicate corresponding parts.

Referring now to the said drawings, the reference numeral 1 designates the novel fruit press of this invention as a whole. Press 1 comprises a hollow rectangular base 2 to which are attached upwardly extending corner angle bars 3. The corner angle bars 3 extend upwardly from the base 2 and are interconnected at their upper ends and substantially midway of their height by transverse bars 4. Additional bars 5 interconnect the transverse bars 4. Bars 4 and 5 together provide a substantially rectangular frame 6 to which vertical slats 6 are attached, as by rivets 7, thereby forming the press body or crib 9 of the press. Slats 6 are spaced slightly from one another to permit the excretion of fruit or other juices therebetween. An additional bar 8 is illustrated as encompassing or surrounding the press body 9 of the press midway of the height of the slats 6.

The press body 9 of the press is open at its top and bottom and is adapted to have its bottom closed by a removable bottom member or bed 10 which is also formed of slightly spaced slats 11. The removable bed 10 is provided at its underside with a sump or drain pan 12, preferably made of metal, which drain pan is adapted to catch liquid passing downwardly through the spaces between the slats 11 of the bed 10 and serves to convey this liquid through a central hole or aperture 13 provided therein to a spout 14 formed on pan 12, which spout is adapted in turn to convey the liquid to a suitable receptacle (not shown) placed at the front of the machine. The bed 10 is of greater width and depth than the press body or crib 9 of the press so that liquid excreted through the sides of the crib will run down and flow through the slots in the bed 10 and into sump 12.

A pair of spaced plates or runners 15 are secured as by rivets, to the under surface of the sump 12 at the sides of the bed 10, which runners are adapted to rest upon and are slidably over angle bars 16, which extend from the front to the rear of the ma-

chine and are positioned adjacent the frame uprights 3. A pair of transversely spaced angle bars 17 are secured to the underside of sump 12 as by rivets and extend alongside of the runners 15. Angle bars 17 serve as stiffening members for the bed 10 and are interconnected at their forward ends by a transverse handle bar 18 (see Figs. 1 and 2). By grasping handle bar 18, the bed 10 is adapted to be pulled forwardly causing the runners 15 thereof to slide over the angle bars 16 at the sides of the machine frame. In this way the bed 10 may be removed completely from the press.

In order to provide for the easy removal of the bed 10 from the press in use, the angle bars 16 are arranged to be vertically movable so that the bed 10 may be lowered to free the same from the frictional engagement of compressed pulp within the press body of the machine. This vertical movement of the angle bars 16 is accomplished by means of cams 20 which are pivotally mounted as on screws 21 threaded into the angles 3 (see especially Figs. 2, 4 and 5), there being two cams 20 at each side of the machine. Cams 20 have curved arms 22 formed thereon and the arms of these cams extend downwardly at each side of the machine and are interconnected by horizontal links 23 which have forward offset end portions forming handles 24 (Figs. 1 and 4). By pushing handles 24 rearwardly, cams 20 are turned about their pivotal screws 21 to their upright positions to effect the raising of angle bars 16 and hence the raising of bed 10 so that this bed may be jammed against the bottom of the press body, whereas, when handles 24 are pulled forwardly the angle bars 16 are lowered so that the bed may be lowered away from the bottom of the press body. Figs. 1, 2 and 3 show the bottom or bed 10 in its raised position, whereas Fig. 4 shows this bed 10 in its lowered position ready for removal from the machine.

In order to perform the pressing operation, the machine is provided with a removable plunger or cross-head 25 which is slidably mounted for vertical movement within the press body of the machine. This plunger consists of a plurality of slightly spaced slats which are held together by angle bars 26 extending transversely of these slats. A yoke 27 extends transversely of the machine and lies between the angle bars 26 and is secured to these angle bars as by rivets. As plunger 25 moves up and down within the crib, the yoke 27 also moves up and down, this yoke extending through slots provided between adjacent slats 6 at the sides of the crib.

In order to provide for the complete removal of the yoke 27 as well as for the vertical movement thereof within the crib, the bars 5 at the top of the machine and the bar 8 of the machine are vertically slotted or di-

vided transversely to accommodate such movement of this yoke 27. The yoke 27 carrying the plunger 25 is urged upwardly by coil compression springs 28 positioned within hollow retaining cylinders 29 mounted at the sides of the press body 9. Retaining cylinders 29 are mounted on the lower offset ends of plates 30, which plates in turn rest upon angle bars 31 secured to the frame members 3. Screws 32 extend through apertures in the angle bars 31 and through aligned apertures in the retaining cylinders 29, to thereby act to hold these cylinders in fixed position upon the frame of the machine. Coil compression springs 28 are preferably secured at their lower ends to the screws 32. The retaining cylinders 29 are split transversely at 33, for the greater portion of their lengths to receive the yoke 27 and to permit vertical movement of this yoke.

The ends of the yoke 27 have depending hangers 34 secured thereto. The hangers 34 are apertured for receiving removable hooks 37 to which are attached cables 38 of a power transmission means. Cables 38 extend downwardly from the hooks 37 and are wrapped around pulleys 39 which are fixed upon a transverse shaft 40 that is mounted in bearings 41 provided on the frame of the machine. Brackets 52 are mounted on the angle bars 16 and carry rollers 53 for engaging the cables 38 and for causing these cables to extend straight downwardly from the hooks 37, so that the pull of this cable upon the yoke 27 will be a vertical pull and will not tend to cause this yoke to bind in the slots 33 of the retaining cylinders 29.

A ratchet wheel 42 is fixed upon one end of the shaft 40 and is adapted to be actuated by a pawl 43 that is pivotally mounted upon a hand lever 44 which is turnably mounted on the hub 45 of ratchet wheel 42. Pawl 43 may be released from engagement with the ratchet wheel 42 at will by means of releasing linkage 46 of well known construction. By manipulating hand lever 44 the pawl 43 may be caused to rotate ratchet wheel 42, thereby rotating shaft 40 and the pulleys 39 so that the cables 38 are wrapped thereon, thereby effecting the downward movement of the plunger 25 against the tension of springs 28 and against the resistance of any fruit or other material which may be contained within the press body 9.

A stop pawl 47 is pivoted upon the base 2 and engages ratchet wheel 42 for preventing reverse turning of this wheel when the hand lever 44 is being pushed backwardly. A coil spring 48 holds stop pawl 47 in engagement with the teeth of ratchet wheel 42. A foot lever 50 is pivotally supported upon the base 2 and a link 51 interconnects this foot lever with stop pawl 47. By pressing downwardly upon foot lever 50, pawl 47 may be caused to disengage ratchet wheel 42.

overcoming said spring means and for forcing said plunger downwardly within said press body against the resistance of any material therein, a removable bed for closing the bottom of said press body, means for supporting said bed on said frame, said supporting means being operable to move said bed vertically with respect to said press body, whereby said bed may be moved either upwardly into closing and abutting engagement with the bottom of said press body as in preparation of compressing material therein, or downwardly away from said press body bottom as for the purpose of disengaging said bed from the compressed material within said press body after an operation of said plunger and in preparation of removing said bed and the compressed material from said press.

3. In a press of the kind described, in combination, a frame, a hollow press body supported on said frame, said press body being open at its top and bottom, a plunger adapted to be inserted into the top of said press body for movement therein, means mounted on said frame and connected to said plunger for moving said plunger downwardly within said press body to compress material therein, a removable bed for closing the bottom of said press body, cams pivotally mounted at the sides of said frame and arranged in supporting relation with respect to said bed, said cams being manually operable to move said bed vertically with respect to said press body, whereby said bed may be moved either upwardly into closing engagement with the bottom of said press as in preparation of compressing material therein, or downwardly and away from said press body as for the purpose of disengaging said bed from the compressed material within said press body after an operation of said plunger, whereby said bed is freed and may readily be moved from said press.

4. In a press of the kind described, in combination, a frame, a hollow apertured press body supported on said frame, said press body being open at its top and bottom, a removable plunger adapted to be inserted into the top of said press body for movement therein, said plunger having a yoke extending outwardly of said press body, compression springs carried by said frame and engaging said yoke for urging said plunger upwardly within said press body, manually operable ratchet transmission means mounted on said frame for connection to said yoke to effect downward movement of said plunger against the tension of said compression springs, whereby material within said press body is compressed, a removable apertured bed for closing the bottom of said press body, said bed being provided with a sump thereunder and a spout connected to said sump, whereby juices flowing through the apertures in said press body and in said bed will be col-

lected by said sump and delivered through said spout to a suitable container, cams pivotally mounted at the sides of said frame, and bar members mounted on top of said cams for supporting said bed, said cams being manually operable to move said bar members to effect vertical movement of said bed with respect to said press body, whereby said bed may be moved either upwardly into closing engagement with the bottom of said press body as in preparation of compressing material therein, or downwardly and away from said press body as for the purpose of disengaging said bed from the compressed material within said press body after an operation of said plunger, said bed then being readily removed from said press by sliding the same transversely of said bar members.

In testimony, that I claim the invention set forth above I have hereunto set my hand this 16th day of September, 1931.

A pulp pan 54 is positioned below the bed 10 and is adapted to catch the pulp forced out of the press body 9 after the bed 10 has been removed from the machine. Pan 54 has a transversely extending plate 55 secured, as by soldering or welding, to the bottom thereof. Plate 55 is slidably mounted on angle bars 56 which are fixed to the frame members 3. A handle 57 is secured to the forward edge of plate 55. By pulling upon handle 57, the pan 54 may be removed from the machine.

In use, to place fruit or other material into the press body of the machine for pressing, foot lever 50 is depressed while at the same time the releasing linkage 46 is manipulated to disengage pawl 43 from ratchet wheel 42 so that this ratchet wheel is free to revolve under the action of springs 28, which springs force yoke 27 upwardly, unwinding cables 38 from pulleys 29. Yoke 27 may then be raised manually so as to completely remove plunger 25 from the body 9. The bed 10 is inserted into position in the machine and the handles 24 are pushed rearwardly to cause the bed to be pressed firmly against the bottom of the press body 9, as illustrated in Figs. 1, 2 and 3. The fruit to be pressed is then dumped into the crib and rests upon the bottom or bed 10. The plunger 25 is then reinserted into the crib and, with the foot lever 50 released and the pawl 43 in engagement with the teeth of ratchet 42, the hand lever 44 is manipulated to revolve ratchet wheel 42 and effect the turning of pulleys 39 so that cables 38 are pulled downwardly, thereby overcoming the tension of springs 28 and causing the yoke 27 to move plunger 25 downwardly within the body 9 to compress the material within this press body.

Owing to the relatively great leverage or mechanical advantage of the hand lever 44, a relatively slight pull upon this lever will cause the plunger 25 to exert an enormous pressure upon the material within the press body, so that all juices of the material are excreted through the slots between the slats of the press body. These juices flow into the sump 12 and from thence into the spout 14 from which they are delivered into a suitable receptacle. After the fruit or other material has been completely compressed, the pressure of the plunger 25 upon the same may be released by releasing the ratchet wheel 42, which releasing action is accomplished by depressing the foot lever 50 and operating releasing linkage 46 to disengage pawl 43 from the ratchet wheel.

In order to remove the pulp from the crib, the handles 24 are pulled forwardly thereby lowering the bed 10 into the position shown in Fig. 4 and enabling easy removal of this bed from the machine. Hand lever 46 is then again manipulated to move the plunger 25 downwardly and force the pulp into the pan

54 after which the same may be removed from the machine.

It will be noted that the fruit press of this invention is of extremely simple construction and is powerful in its action. The novel construction of the machine providing for the lowering of the bed 10 enables the easy removal of this bed regardless of the pressure which has been previously exerted upon the material within the press body. The lowering of the bed removes the same from frictional engagement with the compressed material in the press body and hence enables the ready forward sliding of the same outwardly of the machine.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. In a press of the kind described, in combination, a frame, a hollow press body supported on said frame, said press body being open at its top and bottom and having apertured side walls, a removable plunger adapted to be inserted into the top of said press body for movement therein whereby material contained within said press body may be compressed, a removable, apertured bed for closing the bottom of said press body, means for supporting said bed on said frame, said supporting means being operable to move said bed vertically with respect to said press body, whereby said bed may be moved either upwardly into closing engagement with the bottom of said press body as in preparation of compressing material therein, or downwardly away from said press body bottom as for the purpose of disengaging said bed from the compressed material within said press body after an operation of said plunger and in preparation of removing said bed and the compressed material from said press, said bed having a greater width and depth than said press body so that liquid excreted through the side walls of said press body will flow downwardly and through the apertures of said bed.

2. In a press of the kind described, in combination, a frame, a hollow press body supported on said frame, said press body being open at its top and bottom, a plunger adapted to be inserted into the top of said press body for movement therein whereby material contained within said press body may be compressed, spring means mounted adjacent said press body and acting on said plunger for urging said plunger upwardly within said press body, transmission means carried by said frame and connected to said plunger for
